UNITED STATES PATENT OFFICE.

WILLIAM B. VANDEGRIFT, OF BRANCHVILLE, ALABAMA.

COMBINATION IRONING-TABLE AND STEP-LADDER.

No. 833,097.

Specification of Letters Patent.

Patented Oct. 9, 1906.

Application filed October 8, 1904. Serial No. 227,655.

To all whom it may concern:

Be it known that I, WILLIAM B. VANDEGRIFT, a citizen of the United States, residing at Branchville, in the county of St. Clair and

5 State of Alabama, have invented new and useful Improvements in a Combination Ironing-Table and Step-Ladder, of which the following is a specification.

This invention relates to a combined ironing-table and step-ladder; and the primary object of the same is to provide a simple and effective organization of elements which may be quickly adjusted and arranged to convert the improved device into an ironing-table or 15 a step-ladder, and thereby have one device capable of serving two different purposes.

The invention consists in the construction and arrangement of the several parts, which will be more fully hereinafter set forth.

20 In the drawings, Figure 1 is a perspective view of the improved device arranged as an ironing-table. Fig. 2 is a side elevation of the device as shown arranged by Fig. 1. Fig. 3 is a perspective view of the improved device arranged as a step-ladder. Fig. 4 is a longitudinal vertical section through the upper part of the device shown by Fig. 3. Fig. 5 is a transverse vertical section of Fig. 2 and is also partially broken away. Fig. 6 is a 25 detail perspective view of one of the connecting-hinges.

Similar numerals of reference are employed to indicate corresponding parts in the several views.

30 The numeral 1 designates an ironing-table of the usual shape, having parallel guides 2 secured to the under side thereof and spaced apart from each other. The guides have their inner opposing edges open and are connected at one end by a cross-support 3. The opposite ends of the guides adjacent to the reduced extremity of the board 1 are open, and therein is slidably mounted a supplemental pressing-board 4 for use in ironing trousers 35 or other analogous devices. This supplemental pressing-board 4 is projectible from the under side of the board 1, as clearly shown by Fig. 1, and is held in immovable position either when projected or drawn under the 40 said board 1 by a set-screw 5, extending through the inner extremity thereof and adapted to impinge against the under side of the said board 1. Rigidly secured to the ironing-board adjacent to the strip 3 is a 45 head-block 6, which serves as the top rest of the ladder, which will be hereinafter more

fully explained. The head-block 6 is held firmly against the outer edge of the strip 3 and is rendered stable by oblique braces 7, extending therefrom to the said strip. 60

Secured at an intermediate point on the under side of the board 1 against the guides 2 are stop-cleats 8, one on each side of the board, each cleat having one end 9 cut at a downward angle of inclination and also 65 formed with an under angular notch 10 in the lower edge thereof. These cleats provide means for supporting the ironing-board at different elevations. When the ironing-board 1 is disposed in horizontal position for 70 use, the head-block 6 extends outwardly therefrom at an angle of inclination; but when the device is arranged as a step-ladder said head-block assumes a horizontal position. 75

The ladder member 11 is movably attached to the end of the board 1 having the head-block 6 secured thereto by means of elongated strap-hinges 19, provided with arms 12 and 12', one member of each hinge being 80 secured to the outer side of the one guide and the remaining coöperating member of such hinge to the outer side of the adjacent portion of one of the rails 14 of the ladder member. The rails 14 of the ladder member are 85 provided at regular intervals with step-boards 15, and at an intermediate point the edges of the rails have seat-slots 16 extending thereinto for a purpose which will presently appear. When the device is arranged as an 90 ironing-board, the ladder member 11 is projected thereunder at an angle and serves as a leg or support, and coöperating therewith is an auxiliary support, which consists of opposite side strips or bars 17, connected by a 95 cross-rod 18 and pivotally attached by means of rivets or analogous devices 19^a to the rails 14 of the ladder member 11, nearer the end of the latter, which is attached to the board. When the device is arranged as a ladder, 100 the auxiliary leg attachment having the connected side strips or bars 17 fold against or over the outer sides of the rails 14 of the ladder member and the cross-rod 18 enters the seat-slots 16, as clearly shown by Fig. 3, thus 105 disposing the said auxiliary leg attachment in such position as not to interfere with the use of the ladder member. When the device is arranged as an ironing-board, the ends of the auxiliary leg attachment farthest from 110 the connecting-rod 18 are brought into contact with the ends 9 or notches 10 of the cleats

8, and the said attachment in such arrangement is disposed at a reverse angle to the ladder member. The latter being greater in length projects outwardly toward the reduced end of the board 1 and supports said board in a manner which will be readily understood.

The connected ends of the hinged members 12 and 12' are projected toward each other a sufficient distance to allow the ladder member 11 to have sufficient play or ample movement in the conversion of the device from an ironing-board to a step-ladder, or vice versa, and the ends of the rails 14 adjacent to the connected ends of the hinge members bear against the inner side of the head-block 6, said ends being cut at an oblique angle to cause a firm engagement thereof with the head-block. The ends of the said rails 14 bearing against the head-block 6 when the device is arranged as a step-ladder prevents the ladder member and board from spreading apart, a sufficient resistance being set up between the ends of the rails 14 and the head-block to resist considerable weight pressure brought to bear on the ladder member when the latter is in use without liability of splitting or breaking the said head-block, especially in view of the braces 7, which materially strengthen the said head-block. The ends of strips 17 and the rails 14, which are adapted to contact with the floor or other base rest, are also cut at an angle for obvious reasons.

When the device is arranged as a step-ladder, the board 1 serves as the resisting support for the ladder member 11, as clearly shown by Fig. 3, and the use of the improved device as a step-ladder does not injure the ironing-board in the least. The improved device

may be reduced to compact form by folding 40 the ladder member, carrying the auxiliary leg attachment against the under side of the board. The board is adapted to be supplied with the usual cushion and covering, and sufficient space is provided for movement of the 45 auxiliary pressing-board 4 to permit the latter to also have applied thereto a covering, if desired.

It will be understood that changes in the proportions, dimensions, and minor details 50 may be resorted to without departing from the spirit of the invention.

Having thus fully described the invention, what is claimed as new is—

In a device of the class set forth, the combination of an ironing-board having grooved parallel guides on its under side, a pressing-board slidably disposed within said grooves, a cross-piece at one end of guides, and a head-block on the cross-piece and supported by 60 braces attached thereto, a ladder hinged to the guides by strap-hinges on its outer sides and the sides of the guides, and having its upper ends bearing against the head-block to prevent the ladder and board from spreading 65 apart when the device is arranged for use as a step-ladder; an auxiliary support pivotally secured to the ladder, and cleats on the guides adapted to receive one end of the auxiliary support when the device is arranged for 70 use as an ironing-board.

In testimony whereof I affix my signature in presence of two witnesses.

WILLIAM B. VANDEGRIFT.
